LIQUID FUEL BURNER

James L. Breese, Santa Fe, N. Mex., assignor to
Oil Devices, Santa Fe, N. Mex., a limited partnership of Illinois

Application January 13, 1944, Serial No. 518,047

10 Claims. (Cl. 126—93)

The present invention relates to an improvement in generator type burners in which a substantial supply of liquid fuel is maintained in a storage zone or container adjacent the mixing chamber. One purpose is to provide an improved means for controlling the air supply to such a burner.

Another purpose is to provide air supply control means responsive to changes in heat conditions adjacent the burner.

Another purpose is to provide means for pre-heating the air delivered to a generator burner.

Other purposes will appear from time to time throughout the specification.

I illustrate the invention more or less diagrammatically in the accompanying drawing, wherein:

Figure 1 is a vertical axial section;

Figure 2 is a partial plan view on an enlarged scale;

Figure 3 is a section along the line 3—3 of Figure 1 on an enlarged scale;

Figure 4 is a partial vertical section on an enlarged scale through a variant form of the device.

Like parts are indicated by like characters throughout the specification and drawing.

Referring to the drawing, 1 generally indicates a container adapted to receive a substantial supply of liquid fuel indicated therein as at 2. The container is shown as having a removable cover 3 with a central aperture 4 surrounded by a generally cylindrical upwardly extending flange 5. The cover is apertured as at 6 to permit the passage of a generally vertical air inlet duct 7, the bottom of which is formed with air outlet slots 8 shown as extending above and below the level of fuel 2 in the container 1. The slots are so located that a supply of air is admitted to the interior of the container 1 at or adjacent the level of the fuel.

10 generally indicates a burner pot having a plurality of primary air apertures 11 spaced circumferentially thereabout and located at various distances from the top thereof. Adjacent the top of the pot is located a single row of larger and more closely spaced secondary air inlets 12 shown as upwardly and inwardly tilted. The pot is shown as having an outwardly extending flange 13 on which is mounted a downwardly depending skirt 14, the bottom of which is open at 15 to permit air to enter the space about the pot.

16 indicates a flame ring partially closing the top of the pot and centrally apertured as at 17. 18 is an upper drum or combustion chamber closed by a top 19 from which extends upwardly any suitable outlet 20. The air tube 7 is shown as terminating adjacent the top 19 of the drum 18. It

5 may be secured to the drum by any suitable surrounding strap 21. Surrounding its open top is a removable band 22 which pivotally supports a cover plate 23 which may be rotated into and out of closing position about the center 24. The tube 7 is also provided adjacent its top with an air inlet opening 25 which may be controlled by a flexing leaf or bi-metal bar 26. The member 26 is shown as riveted or otherwise secured to the drum 18 as at 27. It is provided at its outer end with a curved portion 28 adapted to engage and conform to the face of the tube 7 surrounding the aperture 25. It will be understood that any other suitable means may be employed for insuring substantially complete closing of the aperture when the leaf 26 flexes to closing position.

In the form of Figure 4, I employ the drum 18 and its top 19 has means for controlling or modulating the inflow of air through the tube 7a. I illustrate the tube as having secured thereto a bracket 30 to which is pivoted as at 31, a closure 32. At the opposite side of the pivot 31 is the counter-weight 33. 34 is an adjustable collar, shown as screw threaded at the top of the member 7a. It 15 will be understood that variations in the height of the drum 18 occur upon changes in its temperature and the expansion of the material of which it is composed, and such variations are employed to move the member 32 toward and away from the leaf 26.

20 It will be realized that whereas I have shown and described an operative device, still many changes in the size, shape, number and disposition of parts may be made without departing materially from the spirit of my invention and I wish, therefore, that my showing be taken as in a large sense as diagrammatic.

25 The use and operation of the invention are as follows:

30 I provide a generator burner which includes a fuel container 1, a burner pot 10, and a combustion chamber 18. A supply of air is admitted to the fuel chamber 1 through the air inlet tube 7. This air flows into the chamber 1 at the level of the fuel and is effective to maintain partial combustion which produces sufficient heat to vaporize liquid fuel from the surface of the fuel body 2. This vaporized liquid fuel flows upwardly through the neck 4 into the mixing chamber 10. It there 35 receives a supply of primary air through the inlets 11 which produce a primary mixture of vaporized fuel and air. This mixture continues its upward or forward flow until it receives the secondary air delivered upwardly and inwardly through the tilted secondary air inlet apertures 12. This pro-

duces a final and fully combustible mixture which then flows into the combustion chamber 18. Combustion of the final mixture begins substantially at the level of the secondary air inlets 12 and the flame rises a substantial distance upwardly into the chamber 18, which serves as a heat radiating body for the space to be heated.

Since the exposed area of liquid fuel from which vaporization takes place is substantially constant, combustion is varied by varying the initial air supplied to the chamber 1. This can be done by manual setting, as by employment of the cover plate 23 which can be manually moved from full closing to full opening position. I preferably employ in addition to means for manual adjustment, automatic means for modulating or controlling the supply of air in response to changes in heat conditions in the burner. In the form of Figures 1 to 3, I provide, in addition to the manually controllable member 23, an air inflow aperture 25 which is controlled by the flexure of the warping bar 26. At one limit of the movement of the bar, the curved portion 28 engages the exterior of the tube 7 and completely closes the aperture 25. At the other limit of movement of the bi-metal bar 26, it is moved as in Figure 3, to a position which leaves the aperture 25 substantially unrestricted.

In considering the general theory of the operation of the device, the oil is raised upwardly in the burner for mixing and combustion, by converting it into a gas or vapor, which may rise or flow by its own thermal expansion, or may be drawn upwardly to the burner by natural draft.

If desired, any suitable fan means not herein shown, can be employed for forcing the vaporized fuel upwardly or forwardly. Although the fuel level in the base or bottom container 1 varies, it is not the level of the fuel or the mass of fuel in the storage zone which determines the rate of combustion. The amount of fuel burned is controlled by the amount of air admitted through the tube 7.

In Figures 1 to 3, I illustrate the inlet inflow of air to this tube as controlled both manually and thermally.

In Figure 4, I illustrate a purely thermal control, subject to a manual setting by variation of the location of the collar 34. The rate of air flow or the variation of the rate of air flow, into the lower chamber 1 controls the amount of fuel that is burned. It may be advantageous for starting, to employ a wide open air inlet passage. In the form of Figure 1, the cover 23 may be moved to the wide open position. It must be kept in mind that there must be some flow at all times if continuous operation is to be maintained. Since the only means for getting fuel into the pot 10 is to convert the fuel into a gas or vapor, enough air must be admitted to the chamber 1 to maintain the combustion necessary for the vaporization of the fuel. The more air which is admitted, the greater the rate of combustion. It is impractical to rely on radiant heat thrown down from the burner above to vaporize the fuel in the chamber 1.

The air admitted through the slots 8 should be in sufficient quantities not merely to maintain the combustion necessary for the vaporization of fuel from the body 2, but also to provide an excess supply of oxygen. It is essential not merely to maintain a fuel vaporization flame in the container 1 but also to carry some flame and unburned oxygen up into the pot 10 so that

when the additional supply of oxygen is provided through the apertures 11 and 12, combustion will take place. In effect, the ignition of the final mixture may take place from the tip of flame extending upwardly or outwardly from the vaporization zone of the container 1 to the mixing zone in the pot 10.

After combustion has been initiated, the member 23 may be moved to closed or partially closed position and the further operation of the burner may be left to the operation of the bi-metal bar 26. When the drum heats above a predetermined temperature, the warping bar can be set to move toward aperture closing position in relation to the aperture 25. An increase in the heat of the burner thus reduces the supply of air flowing downwardly through the tube 7 and this in turn reduces the amount of fuel vaporized and thus cuts down the fire. As the temperature in the drum 18 drops, the bi-metal bar 26 tends to move toward the open position and admit more air. Thus a modulating, automatic, thermally responsive control is provided. The minimum supply of air may be varied by variation of the position of the closure 23 or in the form of Figure 4 by varying the position of the member 34.

I claim:

1. In a liquid fuel vaporizing burner, a fuel container and a liquid fuel vaporizing chamber adapted to serve as a base for the burner and to contain a substantial supply of liquid fuel, a heater drum located above the fuel container, a hydroxylating burner pot interposed between the heater drum and the fuel container, the interior of the pot being in communication with the interior of the fuel container and with the interior of the heater drum, said pot having a plurality of air inlet apertures therein, a duct supplying air to the vaporizing chamber, mounted on said container and extending upwardly along said heater drum and in close proximity thereto, and means for varying the inflow of air through said duct to the interior of the fuel container in response to changes in temperature of said heater drum.

2. In a liquid fuel vaporizing burner, a fuel container and a liquid fuel vaporizing chamber adapted to serve as a base for the burner and to contain a substantial supply of liquid fuel, a heater drum located above the fuel container, a hydroxylating burner pot interposed between the heater drum and the fuel container, the interior of the pot being in communication with the interior of the fuel container and with the interior of the heater drum, said pot having a plurality of air inlet apertures therein, a duct supplying air to the vaporizing chamber, mounted on said container and extending upwardly along said heater drum and in close proximity thereto, and means for varying the inflow of air through said duct to the interior of the fuel container in response to changes in temperature of said heater drum, said air supplying duct having an inlet aperture located adjacent an upper portion of said heater drum and a valve therefor and means for moving the valve in response to changes in temperature of the heater drum.

3. In a liquid fuel vaporizing burner, a fuel container and a liquid fuel vaporizing chamber adapted to serve as a base for the burner and to contain a substantial supply of liquid fuel, a heater drum located above the fuel container, a hydroxylating burner pot interposed between the heater drum and the fuel container, the interior

of the pot being in communication with the interior of the fuel container and with the interior of the heater drum, said pot having a plurality of air inlet apertures therein, a duct supplying air to the vaporizing chamber, mounted on said container and extending upwardly along said heater drum and in close proximity thereto, and means for varying the inflow of air through said duct to the interior of the fuel container in response to changes in temperature of said heater drum, said air supplying duct having an inlet aperture located adjacent an upper portion of said heater drum and a valve therefor and means for moving the valve in response to changes in temperature of the heater drum, including an actuating connection between said valve and the heater drum.

4. In a liquid fuel vaporizing burner, a fuel container and a liquid fuel vaporizing chamber adapted to serve as a base for the burner and to contain a substantial supply of liquid fuel, a heater drum located above the fuel container, a hydroxylating burner pot interposed between the heater drum and the fuel container, the interior of the pot being in communication with the interior of the fuel container and with the interior of the heater drum, said pot having a plurality of air inlet apertures therein, a duct supplying air to the vaporizing chamber, mounted on said container and extending upwardly along said heater drum and in close proximity thereto, means for varying the inflow of air through said duct to the interior of the fuel container in response to changes in temperature of said heater drum, and additional manually controllable means for varying the inflow of air through said duct.

5. In a liquid fuel vaporizing burner, a liquid fuel storage and vaporization chamber adapted to serve as the base of the burner, a burner pot mounted on said chamber, said burner pot having a bottom wall, a circumferential side wall and an open top, said side wall being provided with a plurality of air inlet apertures located at various levels and spaced circumferentially about the pot, the bottom wall of said pot being apertured to provide communication between the interiors of the vaporization chamber and of the burner pot, a radiator positioned above the pot and in communication with the interior of the pot, a centrally apertured flame ring partly closing the otherwise open top of the pot, and means for delivering air to the interior of the vaporization chamber in volume sufficient to support a partial vaporizing combustion, including an air inlet duct the lower end of which extends downwardly into the vaporization chamber, an upper portion of said duct being located closely adjacent to and being subjected to the heat of the radiator and valve means for varying the rate of flow of air through said air inlet duct to the interior of the vaporization chamber.

6. In a liquid fuel vaporizing burner, a liquid fuel storage and vaporization chamber adapted to serve as the base of the burner, a burner pot mounted on said chamber, said burner pot having a bottom wall, a circumferential side wall and an open top, said side wall being provided with a plurality of air inlet apertures located at various levels and spaced circumferentially about the pot, the bottom wall of said pot being apertured to provide communication between the interiors of the vaporization chamber and of the burner pot, a radiator positioned above the pot and in communication with the interior of the

pot, a centrally apertured flame ring partly closing the otherwise open top of the pot, and means for delivering air to the interior of the vaporization chamber in volume sufficient to support a partial vaporizing combustion, including an air inlet duct the lower end of which extends downwardly into the vaporization chamber, an upper portion of said duct being located closely adjacent to and being subjected to the heat of the radiator, and heat responsive means subjected to the heat of the radiator for varying the rate of flow of air through said air inlet duct to the interior of the vaporization chamber.

7. In a liquid fuel vaporizing burner, a liquid fuel storage and vaporization chamber adapted to serve as the base of the burner, a burner pot mounted on said chamber, said burner pot having a bottom wall, a circumferential side wall and an open top, said side wall being provided with a plurality of air inlet apertures located at various levels and spaced circumferentially about the pot, the bottom wall of said pot being apertured to provide communication between the interiors of the vaporization chamber and of the burner pot, a radiator positioned above the pot and in communication with the interior of the pot, a centrally apertured flame ring partly closing the otherwise open top of the pot, and means for delivering air to the interior of the vaporization chamber in volume sufficient to support a partial vaporizing combustion, including an air inlet duct the lower end of which extends downwardly into the vaporization chamber, an upper portion of said duct being located closely adjacent to and being subjected to the heat of the radiator, and heat responsive means subjected to the heat of the radiator for varying the rate of flow of air through said air inlet duct to the interior of the vaporization chamber, and additional manually controllable means for varying said rate of air flow.

8. In a liquid fuel vaporizing burner, a liquid fuel containing vaporization chamber, a burner pot mounted on said chamber, said burner pot having a circumferential side wall provided with a plurality of air inlet apertures located at various levels and spaced circumferentially about the pot, a combustion chamber the interior of which is in communication with the interior of the burner pot, duct means for connecting the interior of the burner pot with the interior of the vaporization chamber, and means for delivering air to the vaporization chamber in volume sufficient to support a partial vaporizing combustion, including an air inlet duct adjacent and subjected to the heat of the combustion chamber, and valve means for varying the rate of flow of air through said air inlet duct to the interior of the vaporization chamber.

9. In a liquid fuel vaporizing burner, a fuel container and liquid fuel vaporizing chamber adapted to serve as a base for the burner and to contain a substantial supply of liquid fuel, a heater drum located above the fuel container, a hydroxylating burner pot interposed between the heater drum and the fuel container, the interior of the pot being in communication with the interior of the fuel container and with the interior of the heater drum, said pot having a plurality of air inlet apertures therein, a duct supplying air to the vaporizing chamber mounted on said container and extending upwardly along said heater drum and in close proximity thereto, and means for varying the inflow of air through said duct to the interior of the fuel container in re-

sponse to changes in temperature of said heater drum, the air supplying duct terminating, at its lower end with an air delivering aperture located above the normal level of liquid fuel in the fuel container.

10. In a liquid fuel vaporizing burner, a fuel container and liquid fuel vaporizing chamber adapted to serve as a base for the burner and to contain a substantial supply of liquid fuel, a heater drum located above the fuel container, a hydroxylating burner pot interposed between the heater drum and the fuel container, the interior of the pot being in communication with the interior of the fuel container and with the interior of the heater drum, said pot having a plurality of 15

air inlet apertures therein, a duct supplying air to the vaporizing chamber mounted on said container and extending upwardly along said heater drum and in close proximity thereto, and means 5 for varying the inflow of air through said duct to the interior of the fuel container in response to changes in temperature of said heater drum, including a valve seat at the upper end of said air supplying duct, a valve opposed to said seat and 10 a warping bar on which said valve is mounted, said warping bar being adjacent to and responsive to changes in the temperature of the heater drum.

JAMES L. BREESE.
